DESIGN FOR A FINGER RING

Homer M. Walden, Houston, Tex.; Lievin T. Weber executor of said Homer M. Walden, deceased

Application February 15, 1945, Serial No. 117,972

Term of patent 14 years

(Cl. D45—10)

To all whom it may concern:

Be it known that I, Homer M. Walden, a citizen of the United States, residing at Houston, in the county of Harris and State of Texas, have invented a new, original, and ornamental Design for Finger Rings, of which the following is the specification, reference being had to the accompanying drawing, forming part thereof.

The figure is a perspective view of a finger ring showing my new design, the opposite side of the shank of the ring being the same as that shown. The bars on the head of the ring are each lined to indicate color contrast thereon.

I claim:

The ornamental design for a finger ring, as shown and described.

HOMER M. WALDEN.
